UNITED STATES PATENT OFFICE.

THEODORE H. PROSKE AND ALEXANDER L. PROSKE, OF DENVER, COLORADO.

UPSETTING-MACHINE.

1,322,612.

Specification of Letters Patent.

Patented Nov. 25, 1919.

Application filed December 27, 1916. Serial No. 139,230.

To all whom it may concern:

Be it known that we, THEODORE H. PROSKE and ALEXANDER L. PROSKE, citizens of the United States, and residents of the city and county of Denver and State of Colorado, have invented certain new and useful Improvements in Upsetting-Machines, of which the following is a full, clear, and exact description, such as will enable others skilled 10 in the art to which the invention appertains to make and use the same.

The invention relates to improvements in upsetting machines employing air as a motive fluid, and particularly designed for 15 sharpening drill steels.

The object of the invention is to provide a machine of the class specified for the employment of air as a motive fluid and operable for rapidly upsetting tools, or other articles.

Another object of the invention is to provide a pneumatically operated upsetting machine, particularly for use in sharpening drill steels, wherein the gripping jaws are 25 operated to engage the drill steel by the motive fluid, and successively therewith, the motive fluid is directed to the motor for operating the dolly.

Another object of the invention is to provide a machine of the class specified adapted 30 to be controlled for initially causing the gripping jaws to firmly grip the article to be upset, and, in succession therewith, operating the upsetting dolly.

Another object of the invention is to provide a machine of the class specified, particularly designed for upsetting drill steels, which said machine is pneumatically operable and adapted to be controlled by actuation 35 of the same instrumentality to cause the gripping jaws to engage, or disengage, as the case may be, the drill steel, and for operating the upsetting dolly.

Another object of the invention is to provide gripping jaws for the upsetting machine of such construction that they will firmly grip the drill steel and rigidly hold the same in position to be operated upon by the upsetting dolly, the said gripping 45 jaws being shaped to conform to the shape in which it is desired to upset the drill steel.

Another object of the invention is to provide a pneumatically operated upsetting machine wherein the motive fluid is controlled 50 for both setting and releasing the gripping

jaws and for the actuation of the upsetting dolly.

With these and other objects in view, which will become apparent in the following detail description, the invention will now be described with reference to the accompanying drawings, forming a part hereof.

In these drawings, Figure 1 is a side elevation view of the machine; Fig. 2 is a horizontal cross sectional view thereof; taken on the line 2—2 of Fig. 1; Fig. 3 is an enlarged, detail fragmentary horizontal cross sectional view, taken on the line 2—2 of Fig. 1; Fig. 4 is a cross sectional view, 70 taken on the line 4—4 of Fig. 1; Fig. 5 is a plan view of a portion of the machine, showing the gripping jaws and the eccentrics for operating the same, this view being partially broken away to show the roller 75 bearings against which the eccentrics revolve; Fig. 6 is a plan view of the entire machine, showing the relative positions of the pneumatic hammer, the upsetting dolly and the gripping jaws, the gripping jaws being 80 separated; Fig. 7 is a detail sectional view of the gripping jaws and of the upsetting dolly, and Fig. 8 is a face view of the upsetting dolly.

Corresponding and like parts are referred to in the following description and indicated in all the views of the accompanying drawings by the same reference characters.

Let the numeral 6 designate a cylinder, in which, a piston 7 is reciprocably mounted 90 and adapted to be actuated by means of air admitted to said cylinder 6 through an air chest 8. A piston stem 9 is connected with said piston 7, and extends through the forward end of the cylinder 6. A rack bar 10 95 is secured to the forward extremity of the piston stem, which said rack bar is disposed between two segmental gears 12 and 13, the segmental gears 12 and 13 being provided with teeth 14 that intermesh with the rack 100 bar teeth 15 disposed on opposite sides of the said rack bar 10. The segmental gears 12 and 13 are positioned in a housing 16, which said housing is integrally formed with the cylinder 6, the forward extremity 105 of this housing being enlarged, as shown at 17, to accommodate said segmental gears 12 and 13. The segmental gears 12 and 13 are respectively mounted upon journal shafts 18 and 19, which shafts are journaled in the 110 housing 16 at right angles to the direction of reciprocation of the piston 7. The upper

extremities of the journal shafts 18 and 19 extend above the housing 16, and are connected respectively with eccentrics 20 and 21 on the exterior of the housing 16, the said eccentrics being adapted to revolve horizontally and in the same direction in which the segmental gears 12 and 13 are revolved. Blocks 22 and 23 are movably mounted on top of the housing 16, and are each provided with an opening 24 therein, in which said openings, the eccentrics 20 and 21 are received, the said openings being circular and against the walls of which, the eccentrics 20 and 21 rotate, thereby causing the said blocks to simultaneously move toward each other and slightly in a longitudinal direction when the piston 7 is moved forwardly. When the piston 7 is moved in the opposite direction, the eccentrics 20 and 21 cause the said blocks to move away from each other and in a longitudinal rearward direction. The forward movement of the piston 7, through the medium of the rack bar 10, causes the segmental gears 12 and 13 to rotate in the direction indicated by the arrows in Fig. 2, and said segmental gears 12 and 13, being made fast to the journal shafts 18 and 19, will cause the latter to revolve in the same direction together with the eccentrics 20 and 21. Each of the blocks 22 and 23 is provided with a dove-tail recess on its inner edge, in which dove-tail tenons 25 of gripping jaws 26 are adapted to be received, thereby fixedly connecting the gripping jaws 26 with the blocks 22 and 23 so that the same will move with said blocks. A drill steel 27, or other article to be upset is adapted to be engaged between said gripping jaws 26 and firmly held thereby until the upsetting operation has been completed. The particular construction of these gripping jaws 26 for the accommodation of a drill steel will later be explained.

A pneumatic dolly operating motor 28 is mounted on top of the housing 16 parallel with the gripping jaws 26, the same being adapted to actuate the dolly 29, which is positioned directly in front of the forward extremities of the gripping jaws 26 and in line with the extremity of the article to be upset.

The cylinder 6 is provided with air induction passages 30 and 31, which communicate at their outer extremities with the interior 55 of the air chest 8 and at their inner extremities with the interior of the cylinder 6 on opposite sides of the piston 7. A valve piece 32 controls the induction of air through these passages 30 and 31, the said valve piece being movably mounted in the chest 8 to alternately open and close either of the said passages 30 and 31. An operating rod 33 extends into the air chest 8 and passes through the valve piece 32 therein. A nut 34 is 60 threaded on the inner extremity of the op-

erating rod 33, and a spiral spring 35 is interposed between said nut 34 and the valve piece 32. A second valve piece 36 is fixedly mounted upon the operating rod 33, as shown at 37, and moves with the operating 70 rod 33. The valve piece 32 is limited in its movement by means of lugs 38, between which, the said valve piece 32 is disposed. Thus, when the operating rod 33 is moved forwardly, the spring 35 will prevent the 75 said operating rod from sliding through the valve piece 32, but will cause the said valve piece 32 to be moved with the rod 33 until the said valve piece engages with the forward lug 38, whereupon, the spring 35 will be compressed and permit the rod 33 to slide in the valve piece 32 sufficiently for the valve piece 36 to be moved far enough to uncover a port 39. When the valve piece 32 has 80 reached its forward limit of movement, the same has been moved far enough to uncover the forward extremity of the passage 30, and, thereupon, air will be instantly conducted through said passage 30 from the air chest 8 into said cylinder 6 rearwardly of 85 the piston 7, which will result in moving the piston 7 forwardly, operating the gripping jaws 26 toward each other for the purpose of gripping the drill steel 27, through the instrumentalities heretofore described. As 90 the piston 7 is moved forwardly, the air in the path of the piston is forced out of the cylinder through the passage 31, recess 40 in the valve piece 32 and exhaust port 41', the recess 40 of said valve piece having bridged 95 the exhaust port 41' and the outer extremity of the passage 31 when the valve piece 32 was moved forwardly. When the valve piece 32 has been moved to this position, the forward lug 38 will prevent any further forward movement of the said valve piece, and therefore further forward movement of the operating lever 33 will cause the spiral 100 spring 35 to compress, allowing the operating rod 33 to move still further forwardly 110 and carry the valve piece 36 therewith sufficiently to open the port 39. An induction pipe 41 is in communication with the air chest 8, and supplies the latter with motive fluid under pressure. The passage 30 being 115 open to communication with the air chest 8, permits a constant air pressure in the rear of the piston 7, thereby holding the latter forwardly, and the port 39 having been opened by the valve piece 36, communication 120 is established between the air chest 8 and the pneumatic hammer 28 through the medium of an induction pipe 42. Thus, the pneumatic hammer 28 will be caused to operate and exert its energy upon the upsetting dolly 29 through the medium of a tap-pet 43, one extremity of which is received in the pneumatic hammer 28 and the other extremity is received in the upsetting dolly 29, as shown at 44. The operation of the 125 130

pneumatic hammer 28 will cause the upsetting dolly 29 to expend its reciprocating influence against the extremity of the drill steel 27 being upset and accomplish the 5 sharpening and upsetting of said drill steel. Now, the drill steel having been sharpened, the operating rod 33 will be moved rearwardly, carrying the valve piece 36 therewith and closing the port 39, thereby cutting 10 off the supply of motive fluid to the pneumatic hammer 28 and stopping the operation of the latter. Further rearward movement of the operating rod 33 will cause a collar 45 to engage with the valve piece 32 and move 15 the latter rearwardly and cover the forward extremity of the passage 30, which cuts off the pressure in the rear of the piston 7 and establishes the same in front of the said piston by the opening of the passage 31 to communicate 20 with the air chest 8. Thus, the motive fluid entering the front of the piston 7, will move the latter rearwardly, the motive fluid in the path of the piston being forced out of the cylinder through the passage 30, recess 40 and exhaust port 41'. This rearward movement of the piston 7 will cause the rack bar 10 to actuate the segmental gears 12 and 13 in the reverse direction, revolving the eccentrics 20 and 21 25 therewith through the medium of the shafts 18 and 19, thereby causing the eccentrics 20 and 21 to act upon the blocks 22 and 23 for moving the latter away from each other to release the gripping jaws 26 from the drill 30 steel 27. With this separating movement of the blocks 22 and 23, the same will be simultaneously moved away from the dolly 29.

An operating lever 48 is pivoted at one extremity to the housing 16, as shown at 40 49, and with which lever, one extremity of a link 50 is pivoted, as shown at 51, the other extremity of the said link being pivotally connected with the forward extremity of the operating rod 33, as shown at 52. By means of this operating lever 48, the 45 valve pieces 32 and 36 are operated, downward movement of the said operating lever 48 causing the said valve pieces to be moved forwardly for starting the machine 50 in operation and upward movement of said operating lever causing the said valve pieces to move rearwardly for stopping the machine.

Each of the gripping jaws 26 is provided 55 on its inner face with a semicircular groove 53, which receive the drill steel 27. These grooves 53, when the gripping jaws are moved together, form a conical shaped recess 54, which serves to shape the extremity 60 of the drill steel being upset, and which also prevents the drill steel from being driven, or moved longitudinally from the upsetting dolly. The working extremity of the upsetting dolly 29 is of conical shape 65 to conform to the conical shaped recess 54,

as shown at 55. In Fig. 8, a face view of the dolly 29 is shown. The face of said dolly is provided with intersecting grooves 56, which are of triangular shape in cross section, said grooves being adapted to receive the triangular shaped and intersecting cutting edges of the drill steel 27. By reference to Fig. 7, it will be seen that the extremities of these intersecting cutting edges of the drill steel 27 are adapted to be 70 engaged within the semicircular grooves 53, thereby resting said cutting edges against solid material.

Roller bearings 57 are circumferentially disposed in the walls of the recesses 24 of 80 the blocks 22 and 23, and against which the eccentrics 20 and 21 work, thereby reducing the friction to a minimum.

The piston 7 is provided with an annular peripheral recess 58 on one side thereof, 85 in which, a ring 59 is received, and a retaining ring 60 is also received in said recess 58. Suitable packing gaskets 61, formed of leather or other suitable material, are disposed on opposite sides of the 90 ring 59, the said packing gaskets being protruded slightly beyond the periphery of the piston 7. Bolts 61 are passed through the retaining ring 60 and the packing ring 59 and enter the piston 7, as shown at 62, 95 the said bolts 61 serving to hold the two rings, as well as the gaskets 61', in place on the piston 7.

The forward extremity of the housing 16 is provided with an opening 63 there-in, through which the rack bar 10 is adapted 100 to be protruded when the piston 7 is moved forwardly.

The air chest 8 and the cylinder 6 are 105 respectively provided with the usual removable heads 64 and 65.

The openings 20 and 21 in the blocks 22 and 23 are covered by means of plates 66, which are secured to the upper extremities of the journal shafts 18 and 19 by means 110 of fastening devices 67.

While we have described and illustrated herein a specific form of our invention, it is understood that we are not limited thereto and that the same may be modified and 115 varied without departing from the spirit of the invention, or the scope of the appended claims.

Having thus described our invention, what we claim and desire to secure by Letters 120 Patent is:—

1. In a machine of the class described, the combination with gripping jaws, and a pneumatically operable dolly of means for actuating said jaws, comprising a piston, gears operable by said piston, and eccentrics caused to actuate said gripping jaws by said gears. 125

2. In a machine of the class described, the combination with gripping jaws, and 130

a pneumatically operable dolly of means for actuating said gripping jaws, comprising a cylinder, a piston operable in said cylinder, a rack bar connected with said piston and operable by the latter, gears operable by said rack bar, and eccentrics actuated by said gears and operatively connected with said gripping jaws.

3. In an upsetting machine for upsetting drill steels, the combination with a dolly operating motor and gripping jaws for holding the drill steel, of means for actuating said gripping jaws, comprising a gripping jaw actuating motor, a rack bar operable by said gripping jaw actuating motor, segmental gears between which said rack bar is disposed and engaged by said segmental gears, eccentrics operably connected with said segmental gears, and movable blocks carrying said gripping jaws, the said blocks having recesses therein in which said eccentrics are received and adapted to act upon the walls of said recesses to actuate the said blocks.

4. In a machine of the class described, the combination with gripping jaws and a dolly operating motor, of means for actuating said gripping jaws, and said dolly operating motor consisting of a motive fluid supply chest, a motor operatively connected with said gripping jaws, adapted to be placed in communication with said motive fluid supply chest, two valve pieces manually operable for controlling the induction of motive fluid to said dolly operating motor, and said motor for operating said gripping jaws respectively, means for limiting the movement of the valve piece which controls the induction of motive fluid to the motor for operating the jaws, and means whereby later actuation of the other valve piece is required to control the induction of motive fluid to the dolly operating motor.

In testimony whereof, we hereunto set our signatures.

THEODORE H. PROSKE.
ALEXANDER L. PROSKE.
